UNITED STATES PATENT OFFICE

KARL KLAUS LIEBERKNECHT, OF OBERLUNGWITZ, GERMANY

DRIVING MECHANISM FOR FLAT KNITTING FRAMES

Application filed November 29, 1930, Serial No. 499,055, and in Germany December 4, 1929.

This invention relates to an improved driving mechanism for flat knitting frames, especially cotton frames. The characteristic feature of this invention consists of mounting 5 in combination with a slip clutch and two jaw clutches on a main drive shaft, a secondary countershaft connected to the main shaft by reducing gearing of a relatively large ratio, so as to permit the main drive 10 shaft to be driven directly from the drive motor, or indirectly through the reduction gearing. By this arrangement the advantage is obtained that, for working at normal speed, an engaging of the driving shaft free from 15 shocks results and that, when working with reduced speed, i. e. through the intermediary of the reducing gearing, an additional controlling of this slow speed is possible for a further reduction down to zero, i. e. to the 20 stopping of the driving shaft, although the motor is running.

An embodiment of the invention is illustrated diagrammatically by way of example in the accompanying drawing in which:—

25 Fig. 1 shows, partly in section, a front elevation of the driving mechanism.

Fig. 2 is a corresponding part end elevation of the slipping clutch, viewed from the right.

30 From an electric motor 1 or from any other suitable source of power a pulley 4 is driven by a pulley 2 through the intermediary of a belt 3, which pulley 4 is loosely mounted on the main shaft 5 and arranged either in the middle of the frame or on one of the sides of the same. The driving shaft 5 drives the cam shaft in known manner through the intermediary of pairs of gear wheels, arranged on 35 both sides of the frame, these elements not being shown in the drawing.

The pulley 4 has a cavity 6 in which a pin 7 is fixed in axial direction on the body of the pulley. To this pin 7 a friction band 8 is attached, which is placed around a drum 9 keyed on a sleeve 10, which carries the pulley 4. This sleeve 10 runs loosely on the driving shaft 5 and is fitted on each end with a claw clutch 12, the other halves 13 of which 45 claw clutches are fitted on the end faces 50 of slidable sleeves 14 and 15 respectively.

The sliding sleeve 14 is shiftably mounted on the shaft 5 by means of a key or feather 16. This slidable sleeve 14 has a groove 17 in its circumference with which engages the bifurcated end of an arm 18 keyed on a short rod 20 shiftable in bearings 19 of the knitting machine frame. An adjusting handle 21 is fixed on the rod 20 which also carries on its projecting right hand end an arm 22, the bifurcated other end of which engages with the circumferential groove 23 of the slidable sleeve 15. The slidable sleeve 15 carries between the portion having the circumferential groove and its end face fitted with the half 65 13 of the claw clutch, a gear 24 meshing with a narrower spur wheel 25 of a secondary countershaft 26. This secondary countershaft is journalled in bearings 27 of the frame and carries further a pinion 28 meshing with a spur wheel 29 keyed on the driving shaft 5. This back gearing may be otherwise constructed, for instance as reducing gearing, but it works preferably with a transmission ratio of 1:10. 70

The operation of the driving mechanism 75 described is as follows:—

If the handle 21 is pushed to the right, the rod 20 is shifted to the right so that the left hand clutch elements 13 and 12 are engaged with each other, the machine running during the knitting of plain rows at normal speed, about 60 to 70 revolutions of the cam shaft. Owing to the interposition of the slipping clutch 7, 8, 9, 10, the engaging of the clutch is effected almost free from shocks. The elements of the driving mechanism are returned into the normal position shown in Fig. 1 by pushing the handle 21 to the left into its initial position. If the handle 21 is pushed to the left from the normal position, the right hand clutch elements 13 and 12 are engaged also free from shocks. The movements of the driving belt 3 are now transmitted upon the shaft 5 through the gearing 24, 25, 28 and 29. This considerably reduced speed of approximately only 4 to 8 revolutions per minute permits of accurately observing operations at certain times and, if necessary, of disengaging at the correct time, 100

so that the working by hand, which has hitherto been usual, is done away with.

By the interposition of the slipping clutch a further considerable advantage is obtained, 5 as it permits at the reduced speed of the frame, the motor running, an additional regulating of this speed to be effected by means of a hand wheel 31 of known type. By braking by hand, the knitter can further reduce 10 the speed up to zero and thus cause stopping of the working elements at any desired time, it being unnecessary to disengage the motor or the clutch. It is therefore possible for the knitter to carry through an accurate control of the frame when the motor is running 15 and to stop the frame accurately at any desired point similarly to when working exclusively by hand as heretofore. The slipping clutch may have any other suitable construction than that shown by way of example 20 in the drawing.

I claim:—

1. A drive for flat knitting machines comprising in combination with a motor, a driving shaft driven by said motor, a rotatable non-shiftable sleeve arranged on said driving shaft, coupling teeth on both end faces of said sleeve, a drum keyed on said sleeve, a belt pulley loosely mounted on said sleeve, a friction band carried by the pulley and extending over said drum, a coupling sleeve shiftably splined on said driving shaft adapted to be coupled to said non-shiftable sleeve at one side thereof, to directly drive said 25 driving shaft, a second shiftable coupling sleeve splined on said driving shaft on the opposite side of said non-shiftable sleeve, a gear carried by said second coupling sleeve, a counter-shaft, a reducing gearing including 30 the aforesaid gear with a transmission ratio of approximately 1:10 on said driving shaft and counter-shaft and a hand adjusting means on said driving shaft adapted to allow said driving shaft to be turned by hand for 35 an additional reduction of speed down to and including zero when said motor is running 40 and said reducing gear is engaged.

2. A drive for flat knitting machines comprising in combination with the driving 45 motor, a driving shaft driven by said motor, a coupling sleeve slidably splined on said driving shaft, a counter-shaft extending parallel to said driving shaft, a reduction gearing mounted partly on said driving shaft and 50 partly on said parallel counter-shaft, said gearing allowing a transmission ratio of approximately 1:10, a second coupling sleeve shiftably splined on said driving shaft, an element of the reduction gearing carried by 55 said second sleeve, a non-shiftable rotatable sleeve mounted on said driving shaft between said coupling sleeves, connecting parts between the first named coupling sleeve and said element of said reduction gearing for alternately shifting the gear element and asso-

ciated coupling sleeve, a drum attached to said rotatable sleeve, means connected to said rotatable sleeve and having a cavity, a friction band fixed on a pin in the cavity of said means and extending over said drum, and means on said driving shaft for additional hand braking said driving shaft for reducing its speed down to a standstill during the drive of said motor.

In testimony whereof I affix my signature. 75
